(57) **CLAIM**

The ornamental design for a skin cover set for a gaming console and console docking station, as shown and described.

DESCRIPTION

FIG. 1 is a rear elevation view of a skin cover set for a gaming console and console docking station showing a first piece of the set separately for ease of illustration; FIG. 2 is a front elevation view thereof, showing a second piece of the set separately for ease of illustration; FIG. 3 is a front elevation view thereof, showing a third piece of the set separately for ease of illustration; FIG. 4 is a left side elevation view of showing all three pieces of the set together; FIG. 5 is a rear perspective view thereof, showing the first set piece in use on a gaming console; and, FIG. 6 is a front perspective view thereof, showing the second and third set pieces in use on a gaming console dock. It is understood that the third piece of the set shown in FIG. 6, wraps and runs around gaming console.
